UNITED STATES PATENT OFFICE.

JACKSON M. VAN B. ILGENFRITZ, OF BALTIMORE, MARYLAND.

SHIP'S WINDLASS.

SPECIFICATION forming part of Letters Patent No. 242,095, dated May 24, 1881.

Application filed November 15, 1880. (No model.)

To all whom it may concern:

Be it known that I, JACKSON M. VAN B. ILGENFRITZ, of the city of Baltimore and State of Maryland, have invented certain Improvements in Ships' Windlasses, of which the following is a specification; and I do hereby declare that in the same is contained a full, clear, and exact description of my said invention, reference being had to the accompanying drawings, 10 and to the letters of reference marked thereon.

The object of this invention is to reduce unequal wear of the ratchet-teeth and pawls of a windlass; and it, briefly stated, consists in providing the ratchet-disk at the outer end of 15 the head with a flange to prevent the pawl, which rests thereon, from moving outwardly as the same becomes loose from wear.

It further consists in flanging the pawl, which, in connection with the inner ratchet- 20 disk, prevents reverse movement of the wind- lass-head, whereby the said pawl is retained in a central position on the said disk independ- 25 ently of the bolt from which it depends.

In the further description of my said invention which follows reference is made to the accompanying drawings, forming a part hereof, 30 and in which—

Figure I is a top view of the improved wind- lass and the post to which it is secured. Fig. 35 II is an end view of the same. Fig. III is a sectional view of a part of the windlass. Fig. IV is an exterior view of another part of the invention.

Similar letters of reference indicate similar parts in all the views.

A is the shaft of the windlass, adapted to turn in boxes *a*, secured to the post *B*.

C are the windlass-heads, fastened to the shaft *A*. The heads *C* are each provided with two toothed disks, *b* and *c*, the former located 40 at the inner and the latter at the outer end of the head. The pawls which engage with the ratchet-disks *b* and *c* are respectively represented by *d* and *e*.

D are sleeves, into which the handspikes, 45 by means of which the windlass is operated, are inserted, and to which the pawls *e* are pivoted.

E are flanges secured to or forming a part of the ratchet-disks *c*, designed to prevent lateral movement of the free ends of the pawls *e*. Lateral movement of the free end of the pawls *d* is prevented by the projections *f*, which extend from the under side thereof, as shown in the drawings. 50

I claim as my invention—

1. In a windlass, the head *C* and ratchet- 55 disk *c*, combined with the flange *E*, substantially as and for the purpose herein specified.

2. In a windlass, the head *C* and ratchet- 60 disk *b*, combined with the pawl *d*, the said pawl having the projections *f* on its under side, substantially as and for the purpose specified.

JACKSON M. VAN B. ILGENFRITZ.
